WRIST WATCH STRAP

Joseph W. Nienaber, Cincinnati, Ohio

Application November 19, 1953, Serial No. 27,674

Term of patent 14 years

(Cl. D45—4)

Fig. 1 is a top plan view of a wrist watch strap showing my new design, the dotted line showing being for illustrative purposes only;

Fig. 2 is a fragmentary top plan view thereof drawn on an enlarged scale; and

Fig. 3 is a sectional view thereof taken along the line 3—3 of Fig. 2.

My design for a wrist watch strap is characterized by the contrasting stripe near the strap edge in association with the matching stitching as best shown in Fig. 2.

I claim:

The ornamental design for a wrist watch strap, as shown and described.
